UNITED STATES PATENT OFFICE.

OTTO VON BRONK, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

TRANSMITTING ANTENNA.

Application filed September 3, 1921, Serial No. 498,426, and in Germany August 23, 1917.

(GRANTED UNDER THE PROVISIONS OF THE ACT OF MARCH 3, 1921, 41 STAT. L., 1313.)

An application for this invention was filed in Germany August 23, 1917, Patent No. 313,215.

In a normal antenna the radiation is, according to the theory as accepted today, represented by the relation for the radiation resistance,

$$\omega_s = 160\pi^2 \left(\frac{\alpha h}{\lambda} \right)^2$$

where α represents a form-factor, h the height of the capacity above earth and λ the wave length. As to the correctness of the formula there exist doubts based on practical experience. The wide deviations observed can also be explained as a change of α dependent upon λ . But this is certain, that after completed construction of a normal antenna the radiation resistance is still a function of the wave length.

According to the present invention the radiation resistance, within certain limits, can be made independent of the wave length. The drawing Figs. 1 and 2 are diagrammatic representations of two embodiments of the invention. In both cases two antenna-parts are combined into one arrangement. The antenna parts are energized by any convenient and well-known means as by coupling coils supplied by a suitable source of high frequency energy. If both antenna-parts A_1 and A_2 are equally tuned and if only antenna A_1 is energized, then a great part of the electric lines of force are closed through the capacity surface of antenna A_2 . The ammeter J_2 in A_2 will therefore show a rather high current. As the entire arrangement is very much closed, the radiation resistance will be a minimum. By making the outer-coupling stronger, for instance, through the magnetic field of the induction coils L_1 and L_2 the current in A_2 can be brought down to a minimum. Thereby, of course, the current also decreases in A_1 , as indicated by ammeter J_1 . A_1 then radiates as if A_2 were non-existent. A diminution of the radiation resistance through the antenna-part A_2 can also be obtained by changing the tuning of A_2 relative to A_1 .

The radiation can be increased above the amount which was reached by the back coupling resulting in zero current in A_2 , if the antennæ A_1 and A_2 are fed at the same fre-

quency and phase. The maximum is reached when the current in A_1 and A_2 is approximately equal.

Therefore, the radiation resistance can be constantly changed by this means within the limiting values designated below:

(1) Minimum, when A_1 and A_2 are operated at the same frequency with 180° phase difference.

(2) Maximum, when A_1 and A_2 are operated at the same frequency and in phase.

The arrangement, like any radiator, can also be used as receiver.

It will be evident from the facts pointed out that with the above described change of the radiation resistance, a change in the wave length also takes place. If the wave length is to be maintained constant, then the variable factors defining the wave lengths, self-inductance or capacity, must be changed correspondingly.

The drawing shows only two antennæ-parts. The amount of radiation can, as is at once clear, also be determined through several antennæ thus fitted into and onto each other, and changed within limits.

It will be remembered that a closed type of antenna is one in which the radiating circuit is substantially conductively closed on itself. This type of antenna has a relatively low radiating resistance and is inherently a poor radiator. On the other hand, an open type of antenna is one in which the radiating circuit is open to the greatest extent. This type of antenna has a relatively high radiation resistance and is inherently a good radiator.

It will be easily appreciated that in effect the antenna system according to the present invention is changed from a closed type to an open type simply by changing the energization of the antennæ.

When the energization of the antennæ is such that the currents are in phase, then the system operates like two open antennæ in parallel. On the other hand, when the energization of the antennæ is such that the currents are 180° degrees out of phase, then the system operates like a closed antenna system.

I claim:

1. In an antenna arrangement comprising a plurality of transmitting antennæ electrostatically coupled together, the method of

controlling the radiation resistance, comprising the steps of, impressing voltage on one antenna, and then adjusting the amplitude of a voltage impressed on another antenna so that the current in said antenna has some value between the limits of maximum in phase with the current in said first antenna through zero to maximum 180 degrees out of phase with the current in said first antenna.

10 2. In an antenna arrangement comprising

a plurality of transmitting antennæ electrostatically coupled together, the method of controlling the radiation resistance, comprising the steps of impressing voltage on a first antenna, then impressing voltage on a second antenna to oppose the voltage induced by electrostatic coupling with said first antenna, and adjusting said last voltage in amplitude. 15

In testimony whereof I affix the signature.

OTTO von BRÖNK.
